UNITED STATES PATENT OFFICE

2,519,430

PORTABLE DRESSING BOOTH AND SHOWER
BATH APPARATUS

Franklin B. Brown, Los Angeles, Calif.

Application January 2, 1948, Serial No. 242

1 Claim. (Cl. 135—5)

1

This invention relates to portable dressing rooms, and more particularly to a combined portable dressing room and shower bath device for use by bathers, campers, or where bathing facilities are not otherwise available.

A main object of the invention is to provide a novel and improved portable dressing booth and shower stall which is very simple in construction, easy to set up and which may be collapsed to occupy a very small amount of space, making it readily transportable.

A further object of the invention is to provide an improved portable dressing room and shower stall which is composed of simple parts which are inexpensive to manufacture and easy to assemble for use, the apparatus being sturdy in construction, light in weight, and having a wide range of utility, particularly for bathers, campers and for use on picnics and similar excursions.

Further objects and advantages of the invention will become apparent from the following description and claims, and from the accompanying drawings, wherein:

Figure 1 is an elevational view, partly in cross-section of a portable dressing room and shower stall set up for use.

Figure 2 is an elevational view showing the curtain portion of the apparatus of Figure 1 and the top and bottom supports therefor, the curtain portion being shown in collapsed position.

Figure 3 is a top view, partly broken away, of the portable dressing room and shower stall of Figure 1.

Figure 4 is a horizontal cross-sectional view taken on line 4—4 of Figure 1.

Figure 5 is a fragmentary plan view of one of the bottom rigid rings employed in the apparatus of Figure 1.

Figure 6 is an enlarged vertical cross-sectional detail view taken on line 6—6 of Figure 3, showing a portion of the top structure of the apparatus of Figure 1.

Figure 7 is an enlarged cross-sectional detail view taken on line 7—7 of Figure 4.

Referring to the drawings, 11 designates a circular base plate, preferably made of aluminum or other light metal. Secured to base plate 11 adjacent its periphery and at equal angular spacings thereon are four upstanding sleeve members 12. Designated at 13 are vertical post members, each post member comprising a plurality of upper sections 14 and a lowermost section 14'.

Each section of the post members except the lowermost section 14' is formed at its lower end with a reduced projection or dowel 15. The top

2

ends of the sections are each formed with a bore receiving the dowel 15 of the next upwardly adjacent section. The lower ends of the lowermost sections 14' of the post members are received in the respective upstanding sleeve members 12 and secured therein by wing set screws 12', whereby the post members are supported in vertical positions. The post members may be readily taken apart by separating their respective sections.

Removably secured to the top end portions of the post members 13 by means of wing set screws 16 are sleeve members 17 carried by an annular ring member 18, the upper portions of the post members passing through ring member 18 into the respective sleeve members 17. Depending from ring member 18 adjacent its outer periphery are eye brackets 19. Passing through and supported from said eye brackets is a rigid ring 20. Secured to and depending from ring 20 is a cylindrical curtain 21 of canvas or other suitable flexible waterproof or water repellant material. The bottom hem of curtain 21 carries a rigid ring 22.

Secured to the curtain 21 at spaced intermediate levels thereon are additional rigid rings shown at 23. Encircling the curtain 21 and secured thereto intermediate each pair of rigid rings is an elastic band 24, the elastic band 24 acting to contract the curtain inwardly between each adjacent pair of rigid rings when the top annular ring 18 is unsupported by the post members 13.

Each of the rigid rings 23 is formed at the post members 13 with inwardly looped portions 25 in which the post members are loosely received, whereby the rigid rings and the curtain 21 are held against rotation with respect to the post members while allowing the curtain to be raised and lowered as required. The top and bottom rings 20 and 22 are formed with inwardly directed smaller circular rings 26, said smaller rings encircling the upper end portions of the post members 13 at the top ring 20 and encircling the upstanding sleeve members 12 at the bottom ring 22. The bottom ring 22 is free to be moved upwardly on the post members 13 and by its weight tends to maintain the curtain 21 in a taut condition when the booth is set up for use. When the booth is thus set up, as illustrated in Figure 1, entry of the booth is effected by raising the bottom ring 22, which lifts the lower end of cylindrical curtain 21 and enables the user to enter the booth. The weight of bottom ring 22 causes the lower end of curtain 21 to descend to closed position when said bottom ring is released.

The booth may be secured against rocking or tilting by guy cables 27 connected between rings 28 encircling the sleeve members 17 and stakes 29 driven into the ground laterally adjacent the booth.

Supported on the annular ring member 18 are inwardly and upwardly inclined struts 30 having eye portions 31 encircling the respective sleeve members 17. Connected to the inner ends of the struts 30 is a plate member 32 provided with a depending hook 33 from which a bucket or sprinkler pail, such as shown in dotted view at 34, may be supported. The bucket may be provided with a suitable sprinkler head and with a stop cock controlling the flow of water through said sprinkler head.

The top ring 20 is provided with an inwardly spaced arcuate bracket 35 on which is hung an auxiliary depending flexible curtain 36 defining a storage space 37 between said auxiliary curtain and the outer curtain 21. Conventional clothes hangers 38 may be hung on the top ring 20 for supporting clothes in said storage space.

When the booth is to be dismantled for transportation or storage the set screws 16 and 12' are loosened, and stakes 29 are pulled up. This allows the post members 13 to be raised out of engagement with bottom sleeve members 12, whereby the post members may be taken apart and whereby the top post sections 14 may be disengaged from the top sleeve members 17. The curtain 21 is then collapsed vertically to the position shown in Figure 2, the collapse of the curtain being facilitated by the contraction of the elastic bands 23. The post sections 14 and 14' may then be placed inside the collapsed curtain for transportation or storage therewith.

While a specific embodiment of a portable dressing booth and shower stall has been disclosed in the foregoing description, it will be understood that various modifications within the spirit of the invention may occur to those skilled

in the art. Therefore it is intended that no limitations be placed on the invention except as defined by the scope of the appended claim.

What is claimed is:

- 5 A portable booth comprising a flat circular base member, a plurality of vertical post members detachably secured at their bottom ends to said base member in circumferential spaced relation, a horizontal annular member frictionally secured
 10 to said post members in vertical spaced relation with respect to said base member and mounted for slidable movement on said post members, a cylindrical flexible curtain depending from the periphery of said annular member and terminating adjacent said base member, a plurality of rigid rings secured to and encircling said curtain in vertical spaced relation, loop elements formed on said rigid rings and slidably receiving said post members, elastic bands secured to and encircling said curtain intermediate said rigid rings, and an auxiliary flexible curtain element depending from said annular member adjacent the inside of said curtain defining a clothes storage space between the auxiliary element and said
 15 curtain.
